UNITED STATES PATENT OFFICE.

JAMES FRANK GRANT, OF BALTIMORE, MARYLAND.

DESIGN FOR A BADGE OR SIMILAR ARTICLE.

SPECIFICATION forming part of **Design No. 34,197**, dated **March 12, 1901**.

Application filed February 18, 1901. Serial No. 47,884. Term of patent 14 years.

To all whom it may concern:

Be it known that I, JAMES FRANK GRANT, a citizen of the United States, residing at Baltimore, in the State of Maryland, have invented and produced a new and original Design for Badges or Similar Articles, of which the following is a specification, reference being had to the accompanying drawings, forming a part thereof.

Figure 1 is a front view of the badge, showing my new design; and Fig. 2 is a central horizontal section of the same.

As shown by the drawings, the leading or material feature of my design consists of a circle having a serrated circumference, with a circular rim slightly elevated above the face thereof, as plainly shown in Fig. 2, enclosing the central portion of the area of the

same, the space within the rim being ornamented by a field-tent above and two shepherd's crooks crossed below and the space without the rim with lines leading from the rim in all directions, all as shown in Fig. 1.

Having thus fully described my invention, what I claim as new, and desire to secure by Letters Patent, is—

The design for a badge or similar article, substantially as herein shown and described.

In testimony whereof I have signed my name to this specification in the presence of two subscribing witnesses.

JAMES FRANK GRANT.

Witnesses:

ELVIN J. CURRY,
MATHILDE PRAEGER.
